UNITED STATES PATENT OFFICE.

GUSTAV A. ROEDDE, OF VANCOUVER, CANADA.

LOOSE-LEAF BINDER.

SPECIFICATION forming part of Letters Patent No. 730,161, dated June 2, 1903.

Application filed October 10, 1902. Serial No. 126,750. (No model.)

To all whom it may concern:

Be it known that I, GUSTAV A. ROEDDE, residing at Vancouver, in the Province of British Columbia and Dominion of Canada, have **5** invented a new and Improved Loose-Leaf Binder, of which the following is a specification.

My invention seeks to provide a new and improved device designed for binding loose **10** leaves or sheets into a book or package form; and it primarily seeks to provide a device of this character of a simple, neat, and effective nature, capable of being conveniently applied for binding sheets of commercial or other **15** papers and for permitting a quick separation thereof when so desired.

In its generic nature my invention comprehends a two-part binder, each part having a member for passing through the apertures in **20** the leaf or sheet provided therefor and working one within the other and having means whereby when the two opposing parts are joined together they will automatically interlock to hold the leaves or sheets firmly in bulk.

25 In its more complete nature my invention includes a pair of clamp members, one of which has a socket to receive the other member, said opposing members having combined therewith automatically-interlocking devices, **30** including a detent having an exposed head or finger-piece that projects in a plane beyond one of the presser portions to permit of readily disengaging the interlocking means and to separate the two-part binder device in a quick **35** and convenient manner.

In its more subordinate features my invention also consists in certain novel details of construction and peculiar combination of parts, all of which will hereinafter appear and **40** be specifically pointed out in the appended claims, reference being had to the accompanying drawings, in which—

Figure 1 is a perspective view of a book of sheets and cover therefor bound together by **45** a preferred form of my invention. Fig. 2 is a view of a slightly-modified arrangement of my invention, the telescopic portions and the presser or clamping members being relatively arranged to project the said telescopic portions over the back of the sheet book-cover. **50** Fig. 3 is a longitudinal section of the parts shown in Fig. 1, taken on the line 3 3 of said

Fig. 1. Fig. 4 is a view of the preferred construction of my binding device detached from the sheet or leaf book. Fig. 5 is a view of the **55** two parts separated. Fig. 6 is a vertical section thereof on the line 6 6 of Fig. 5. Fig. 7 is a detail view of another modification of my invention hereinafter referred to. Fig. 8 is a **60** vertical section of a further modification hereinafter described. Fig. 9 is a detail view of a portion of one of the sheets having the notched end.

In the preferred construction my improved binder devices are coöperatively connected **65** with the package or book of sheets in such manner that only the presser or clamp members of the two-part binder are exposed, as clearly shown in Fig. 1, and in such application of my invention one edge of the book **70** of sheets is suitably cut out or recessed, as at *s*, for the proper fitting therein of the telescopic body portions of the opposing binder members and perforated, as at *s*², for the binding-pins, said construction or binder devices **75** being a preferred one, for the reason that in the use thereof only the clamping or presser members and the finger-actuated detent-head of the locking devices appear to view; but I desire it understood I do not limit myself to **80** the peculiar coöperative arrangement of my binder with the sheet-book, as stated, as the same may be readily varied under my invention, as will hereinafter more fully appear and be defined in the claims. **85**

In the preferred form of my binder device the two parts designated by A and B are telescopically arranged and have adjustments relatively to each other, whereby they may be connected to any ordinary size and thickness **90** of package of leaves or sheets to be bound.

The member A consists of a rectangular hollow body *a*, open at the top and integral with a base or clamp member *a'*, which in practice extends under or over the cover **95** member, as clearly understood from the drawings. By reason of the rectangular shape of the body *a* of the member A it will be readily understood from Figs. 1 and 8 that the same will snugly fit the recessed parts of the **100** leaf-bunch, thereby bringing the outer face *a*² of the member *a* flush with the inner edge *z* of leaf-bunch, which serves to steady and hold the body *a* from loose lateral play, and

- the said flat arrangement of the body a , also provided for fitting said portion a , close up against the outer face of the lapped portions $c\ c'$ of the cover members $C\ C'$ when the binder 5 is used in the manner shown in Fig. 2, the latter arrangement of my binder device being employed when it is desired to bind the leaves or sheets without recessing the edges, as shown in Figs. 1 and 3.
- 10 The body b of the member B is of a size to telescopically engage the hollow member A, and the said member b in the preferred form is also hollow to accommodate a preferred arrangement of spring-actuated detent mechanism presently again referred to.
- 15 The two opposing binder or clamping portions $a'\ b'$ of the parts A and B each have a file-spindle or receiving-pin, the spindle a^2 for the member A being in the nature of a 20 sleeve to receive the solid pin b^2 , projected from the part b' of the member B.
- 25 The cover members $C\ C'$ are each provided with an aperture $c^x\ c^x$, in register with the spindle members $b^2\ a^2$, and in the arrangement of my invention as shown in Fig. 1 the said cover members are also provided with elongated slots $c^2\ c^2$, which are in alinement with the recess s in the sheets S.
- 30 So far as described it will be readily apparent in using my binder device in the form shown in Fig. 1 the body a and the sleeve a^2 of the part A are pushed up through the slot c^2 and the aperture in the bottom cover-section, and after the leaves or sheets are strung 35 thereon the upper clamp or binder member B has its body portion b , with the pin b^2 , slipped through the upper cover-section and brought into telescopic engagement with the hollow body a and the sleeve a^2 of the member A, it 40 being manifest that by reason of the adjustability of the part a relatively to the part b the said parts can be conveniently and quickly adjusted to suit the thickness of the book of sheets and quickly separate the two to add 45 more sheets or to separate the said sheets, as may be desired.
- To hold the two parts A and B firmly interlocked to the desired adjustments, I provide a simple, effective, and conveniently-operated means for connecting the said parts and holding them to their clamping positions. In the preferred construction I provide one 50 end of the hollow body a of the member A with a series of notches a^3 , (it being obvious that instead of notches a ratchet-surface may be substituted,) with which the beveled head d of a spring latch or detent D engages, the said detent D being mounted within the hollow of the body portion a of the member A, 55 and the bevel of the head or dog d is such that in shoving the member b into the member a it will automatically interlock with the said notches a^3 . The latch or detent D also includes a finger-actuated trip d^2 , that projects above the upper face of the part a of the member B, whereby by thumb or finger movement the head d is quickly released from

the notches a^3 to permit the parts A and B being adjusted or separated, the said member b being suitably slotted, as at b^5 , to admit of the proper swing or movement of the latch D, as clearly shown in Fig. 6.

75 The use of the locking element as shown admits of an economical construction and also provides for protecting the spring-actuated latch. Furthermore, the form of locking device described permits of using the binder device inside of the cover ends, as shown in Fig. 1, and for quickly disconnecting or assembling the parts A and B to their proper adjustments.

80 When the form of binder device so far described is used upon the outside of the lapped cover edges, the outer or exposed portions of the members A and B are suitably ornamented, as this arrangement of my invention is especially designed for binding such sheets or valuable papers which do not admit of being cut or mutilated to form the notches S.

85 Another and advantageous feature of my invention is that the peculiar co-operative arrangement of the parts A and B and the interlocking devices connected therewith admits of using the entire binding device inside of the cover members $C\ C'$, as shown in Fig. 8, 90 by reference to which it will be noticed the covers $C\ C'$ are joined to the members A and B by rivets $c^5\ c^5$, and the finger-piece d^2 only is projected to view—that is, above the covers C' .

95 It is obvious the exact arrangement of the detent devices D d^5 (shown in detail in Fig. 6) may be varied. I prefer to use the form shown, however, as it provides for an automatic interlocking of the detent with the notches a^3 when pressing the part b into the part a and also for an easy shifting of the said detent d through the movement of the member d^5 in the direction of the arrow in Fig. 6.

100 In Fig. 7 is shown a further modification 110 of my invention. In this form the same general arrangement of parts shown in the other figures is maintained; but in said arrangement the hollow body of the member A is restricted between its vertical edges to provide 115 a central depressed portion a^x to accommodate a flat spring-detent 10, having a lug 10^a, which in practice passes through the portion a^x to engage with a series of apertures b^5 in the portion b^x of the member B and the body 120 b , which in this arrangement is solid. The spring-detent 10 has its upper end turned out to facilitate the withdrawal of the locking-lug 10^a.

125 From the foregoing, taken in connection with the accompanying drawings, it is believed the advantages and the manner of operating my invention will be readily understood. The assembling of the parts being clear, to separate them it is only necessary to 130 shift the trip member d^2 in the direction of the arrow in Fig. 6, which at once unlocks the two parts and permits the one, B, being pulled up from the other part A, which operation is fa-

cilitated by the spring 12 in the bottom of the member a^2 . (See Fig. 3.)

My invention provides a binder complete in itself apart from the cover, to which it 5 may or may not be attached, as the covers, *per se*, form no part of the invention and may be omitted entirely, as the binder device will act directly on the leaves or sheets. (See Fig. 8.) The form of binder shown forms a simple, neat, and effective substitute for the more or less complicated, expensive, and inconveniently-manipulated binder devices now in general use and especially presents the advantage of being adapted for attaching 15 to any cover when it is desired to bind the sheets or leaves within covers.

I am aware that binding devices have been provided in which opposing clamp members having overlapping back pieces are included 20 and which have interlocking elements.

I therefore claim, and desire to secure by Letters Patent, the following:

1. A binder of the character described, comprising a pair of hollow opposing members having clamping portions for engaging the 25 sheets or leaf-pack, one of said members slideable within the other, and locking devices co-operating with the two opposing members for automatically interlocking them in their adjusted position, said devices including an exposed finger-actuated member for the purposes described.

2. A binder of the class described comprising a pair of separable members, one of which has a hollow body portion extending the 35 entire width of the binder, and a clamping portion projecting at right angles therefrom, and a leaf-penetrating member; the other having a body portion for telescopically engaging the 40 opposing hollow body, a clamping portion and a penetrating-pin, a spring-actuated locking device for interlocking the two members in their adjusted positions, said device including an exposed trip member adapted to be 45 engaged by a finger of the operator for releasing the said two separable members as set forth.

3. A binder of the class described comprising two opposing separable members, one of 50 which has a hollow body, a clamp portion and

a hollow leaf-penetrating sleeve in a plane parallel with the hollow body, the other having a hollow body portion and a penetrating-pin for telescopically engaging the hollow body and sleeve of the opposing members, and a 55 clamp portion carrying the said penetrating-pin; and an automatically-operating device for interlocking the two separate members in their adjusted positions, said device including a finger-trip projecting above the body portion 60 of one of the members for releasing the locking device, substantially as shown and described.

4. A binder of the class described, comprising a pair of separable and opposing clamp members, each having a sheet-penetrating pin, one of said members having a hollow body provided with a ratchet edge extending its length, the other separable member having a hollow body for telescopically engaging 70 the hollow body of the opposing member, and spring-actuated detent devices held within the hollow body of the said other separable member, adapted to automatically interlock with the ratchet edge of the first separable 75 body, said device including an exposed finger-actuated trip for adjusting the detent devices to their unlocked position, as set forth.

5. As a new article, a binder for the purposes described, comprising in combination, a pair of opposing and separable members, A and B, the one A, having a hollow body a , a clamping portion a' and a tubular pin a^2 , said body portion a' having a locking-surface a^3 extended its length, the other member B 85 including a hollow body b , a clamping portion b' and a penetrating-pin b^2 , the latter and the body b , being arranged to telescopically engage with the hollow body a and the sleeve a^2 of the opposing member, the spring-actuated 90 detent D mounted within the hollow body b and a finger-trip for moving said detent D to an unlocked position, said trip including a finger-piece d^2 projected outside the body b , all being arranged substantially as shown and 95 for the purposes described.

GUSTAV A. ROEDDE.
